UNITED STATES PATENT OFFICE.

FREDERICK F. BRUSH, OF LOS ANGELES, CALIFORNIA, ASSIGNOR TO ELEVATOR SAFETY APPLIANCE COMPANY, A CORPORATION OF CALIFORNIA.

ELECTRICALLY-OPERATED ELEVATOR-DOOR CONTROL.

Application filed May 22, 1924. Serial No. 715,047.

My present invention being referred to as an electric elevator door control, it will be understood that the nature of the power employed to effect the movement of the elevator car is immaterial to my invention, my novel control, rather than the elevator to which it may be applied, being essentially electric or electro-magnetic in character.

It is an object of this invention to provide simple and effective means obviating the necessity of providing a separate door operating motor in connection with each door leading into an elevator shaft; and I herein provide means whereby one motor, with suitable electric and mechanical connections, may be so used, if mounted at the top of an elevator shaft or where suitable space and a secure foundation can be provided, as to operate any one of a vertical series of doors; and it is a merit of the design herein described, that, although permitting novel features of interlocking control, the design referred to avoids the use of a multiplicity of relatively movable and wearing parts heretofore associated with each door, and it greatly simplifies all incidental problems of lubrication.

It is a primary object of this invention to provide means for rendering the operation of the lifting mechanism and the door operating mechanism of an elevator interdependent, in a manner and to a degree favorable to the avoidance of accidents; and, in one advantageous embodiment of my invention, I may employ, in addition to usual or preferred means for handling an elevator car, and in connection with the several floor doors of same, novel and effective electro-magnetic means whereby the mentioned single door motor, whether located at the head of a shaft or elsewhere, may, by reciprocating a lever and associated parts, operate, at will, any one of an entire series of doors opposite any one of which said car may alternatively be positioned.

For the purpose last referred to, I may connect the mentioned lever, or its equivalent, with a single wire or cable or other reciprocal transmission element, preferably in the form of an endless flexible loop movable opposite all of the doors in a series; and I may associate with the parts referred to, or other equivalent, zoning and interlocking means permitting the mentioned

door motor to be operated only when a car is within a prescribed zone opposite a floor or only in a predetermined sequence with the opening or closing of an elevator circuit, or permitting the mentioned sequential operation only in case the required circuits are properly energized at the moment when such operations are to be initiated.

It being one important object of my invention to provide means permitting a door to be opened only when a car is suitably positioned relatively thereto, my mentioned zoning means may comprise an over-balancing lever carrying a switch in a door control circuit and movable by means comprising a constantly-energized electro-magnet operatively connected with said lever and automatically moving the same to a switch-closing position whenever a car carrying said electro-magnet is brought opposite any one of a series of fixed and highly permeable plates secured at or near the respective floor levels.

As indicated, a complete embodiment of my invention may involve the use of a plurality of circuits or branches, one of which may be an elevator circuit, to operate or control the up-and-down movements of an elevator car, another being herein referred to as a door-control circuit; and with these I may employ novel interlocking means operable by what I herein term a "magnetic gripper-cam", the operation of a novel camming device referred to being preferably interconnected with the completion of a gripping movement incidental to the manipulation of a door, and the mentioned gripping movement being effected by electro-magnetic means.

One operation of the mentioned interlock may optionally be effected by gravity acting on a cam bar and so controlled by a cam-lock that an automatic remaking of an elevator circuit can be effected only in case current is normally flowing in a gripper-cam circuit; and means may moreover be provided whereby, after a car has once been brought into a zone or position permitting a door to be opened, and a door-opening movement has been started, no mere change in the load upon said car can be effective automatically to break the circuit by which the mentioned door-operating motor may be controlled.

With some repetition, important electro-mechanical features of my present invention may be stated as follows: (1) when my zoning switch is closed, manual operation may 5 energize the coil of a magnetic actuator such as the gripper-cam operating an interlock and energizing a motor; and, before the motor opens a door, it may duplicate contacts adapted to maintain a circuit through 10 the coil of said gripper-cam in order to assure immunity from the results of any untimely opening of a zoning switch in case a cable stretches or contracts by reason of change in car load; (2) the energizing of my 15 gripper-cam is a first and master action effected by an operator; and this promptly opens the elevator circuit; (3) the magnetic gripper-cam must first effect a gripping action, and only in completion of its gripping 20 action can it be effective to operate the interlock and to start motor to open a door; (4) when the single motor starts to open any door, it first cuts out the elevator circuit; and (5) if the magnetic cam burns out during 25 operation, a cam lock maintains the cam bar in elevated position, and elevator circuit open, regardless of the position of any other switch in the same circuit.

It is a further object of this invention to 30 provide a door-operating mechanism permitting easy manual manipulation of any door by a qualified operator inside a car opposite the same; and it is a further object to provide means whereby each door may be 35 automatically and securely locked against unauthorized manipulation from the outside.

My mentioned interlocking means may be adapted to permit the starting of a car only 40 in case the door opposite a car is completely closed; and the respective doors may not only be positively held against unauthorized opening, but normally self-closed by the action of gravity.

In one advantageous embodiment of my 45 invention, I may employ means for imparting to an elevator door, upon the closing of a circuit including the door motor, a horizontal motion which may be practically harmonic; and I may optionally interpose, at 50 some convenient point within the mechanical train by which the rotary motion of said motor is converted into a harmonic motion in a horizontal direction, a "spring switch" adapted, by opening a circuit, to stop the 55 closing of a door, in case of an accidental or deliberate interference with its closing movement.

Other objects of my invention, including 60 novel door operating and locking means, will appear from the following description of an illustrative embodiment thereof, and from the appended claims, taken in connection with the accompanying drawings, in which,

65 Fig. 1 is an elevational view showing the

interior of an elevator shaft containing a car and showing parts of a door operating means comprising an overhead motor.

Fig. 2 is a view of a single elevator door, and parts associated therewith, as seen from the inside of an elevator shaft.

Fig. 3 is a vertical section through an elevator car, this view being taken substantially in a plane indicated by the line 3—3 of Fig. 4.

Fig. 4 is a fragmentary horizontal sectional view, such as might be taken on the line 4—4 of Fig. 3.

Fig. 5 is a similar view showing an alternative type of electro-magnetic gripping means.

Fig. 6 is a fragmentary vertical section through a car and a set of elevator doors.

Figs. 7 and 8 are vertical sections showing details of an electro-magnetic zoning device hereinafter referred to.

Fig. 9 is an elevational detail view showing specific features of my mentioned "magnetic gripper-cam" operating an interlocking device, and a shift- or cam-lock associated therewith.

Figs. 10 and 11 are respectively plan and elevational views of a spring switch hereinafter referred to and optionally employed automatically to break a circuit to stop my door motor.

Fig. 12 is a wiring diagram, parts preferably mounted on a car being shown to the right of the line X—X.

Referring to the details of that specific embodiment of my invention chosen for purposes of illustration, and mentioning first the general relationships between the major elements comprised in my novel organization, 1 may be an elevator shaft within which a car 2 is movable, doors 3 being provided at each of the respective floors opposite which said car may stop.

Referring now to certain mechanical or electro-mechanical devices suitable for embodiment in a complete installation illustrating my invention, each of the mentioned doors may be movable by means of a driving bar 4, whose outer end may be pivotally connected at 5 thereto, and whose inner end may be pivotally connected at 6 to a cross head 7, shown as slidably mounted for vertical movement upon a fixed rod 8, whose ends may be rigidly secured, as by brackets 9, 9', above and below the mentioned door.

It will be understood that a vertical movement of the cross head 7, or its equivalent, may be effective completely to open or close an elevator door, and that a mere release of the cross head 7, after the same shall have been elevated, may be effective automatically to close a door. It will also be obvious that, when the parts are related in the general manner indicated in Fig. 2, although the construction is such as to permit of a manual

opening of a door by the lifting of a cross head 7, the normal horizontal position of a driving bar 4, automatically taken when a door is closed, is such as effectively to lock the door against unauthorized opening, the mentioned operating parts being inaccessible from the outside.

Suitably to support the cross head 7, or its equivalent, in the position referred to, I 10 may optionally employ means such as a spring 9; and, to lubricate the rod 12, I may optionally employ a wiper retained in the position indicated by a dotted line at 10; and I may optionally deliver oil to this wiper 15 by means such as a cup 11, supported upon the spring 9.

Although the described door operating mechanism might be advantageously employed in connection with any preferred 20 means for elevating the cross head 7, instead of mounting such means on a car I consider it advantageous to employ for this purpose means comprising an overhead motor, a reciprocable transmission element movable 25 thereby, and electro-magnetic means comprising a clutch or gripper for connecting said reciprocable transmitting element with a cross head 7 in such manner as to impart to the latter element an upward or down- 30 ward movement suitable to the opening or closing of a door.

Although the mentioned reciprocable transmission element might alternatively be a rod or chain, I have suggested, in Figs. 1 35 to 5 inclusive, the employment of a wire or cable 12, which may be "endless" and may be supported upon fixed pulleys 13, 13', or their equivalents, and may be pivotally connected, as at 14, to a lever 15, or its equivalent, 40 movable directly or indirectly by any suitable motor, such as an electric motor M confined within a suitable housing 16, at the top of an elevator shaft, or wherever suitable room and support may be provided 45 therefor.

It being recognized as advantageous to impart to an elevator or other door a "harmonic" or substantially harmonic opening or closing motion, I consider it advantageous 50 to provide the mentioned motor with transmission means comprising a cam 17, adapted to reciprocate a rod or bar 18, shown as having a pin-and-slot connection at 19 with the mentioned lever 15, the configuration of 55 the cam 17 being preferably such as initially to impart a comparatively slow but powerful movement to a door connected as herein described, the final portion of the stroke being also comparatively slow, and the middle portion thereof being greatly accelerated.

In order to connect the cross head 7 at will with a reciprocable transmission element such as the wire or cable 12, extending throughout an elevator shaft, I prefer 60 to employ electro-magnetic means in a cir-

cuit or branch which may be entirely distinct from that by which the lifting of an elevator car or the descent thereof may be effected or controlled; and my herein illustrated means for the purpose referred to 70 comprises an electro-magnet N S, having poles N and S and serving both for the mentioned gripping effect and for a camming effect hereinafter referred to, this electro-magnet being energized by a cam helix C H, 75 which may be wholly or partially confined within a housing 20, slidably mounted upon a post 21 upon the car 2; and, in order to facilitate the free movement of this housing upon the mentioned post, the latter may 80 advantageously be made hollow to receive a counterweight 22, shown as connected with said housing by a cord 23, extending over a pulley 24. As best shown in Figs. 4 and 85 5, the post and associated parts referred to 90 may advantageously be confined within a separate compartment formed by a partition 25; and the electro-magnet referred to 95 may be rigidly connected with any suitable gripping element such as a jaw 26, adapted, upon the energizing of said magnet, to co-operate, in the gripping of the reciprocable transmission element 12, with a corresponding jaw 27, integral or associated with a cross head 7; and each of the mentioned jaws may advantageously be provided with a serrated or roughened gripping surface of brass or other non-magnetic material, a magnetic gap being preferably maintained, in order to obviate any delay 100 in release, such as might result from a direct contact of magnetic materials.

An alternative form of gripping device, in which the pole pieces of an electro-magnet engage a tongs-like gripping device 105 comprising a pivoted jaw 26' and a fixed jaw 27' is shown in Fig. 5, this construction being illustrated merely to point out the possibility of employing the principle of the lever in assuring a firm grip upon a 110 wire or cable 12, for the purposes referred to.

As mentioned, the electro-magnet N S may be utilized not only for the gripping of a reciprocable transmission element but also for a camming effect in the control of 115 an interlocking device by which a proper sequential opening and closing of elevator and door-control circuits may be assured. For example, I may provide the mentioned electro-magnet with a projecting member such as the pin 28, adapted to serve as a cam engaging a cam bar 29, shown as pivotally supported by parallel links 30, 31, in such manner that the gripping movement 120 of said electro-magnet shall be incidentally effective to move the cam bar 29 toward the adjacent wall of an elevator shaft, thereby lifting and advancing said bar sufficiently 125 to operate an interlocking device of the character illustrated in Fig. 9. This inter-

locking device is shown as comprising a pair of fixed contacts 32, 32', in a relay branch circuit r, r' , hereinafter referred to, and a second pair of contacts 33, 33' in an elevator circuit e, e' , a single circuit closing element 34, upon a lever 35, being shown as connected (by a link 36, pivoted to the cam bar 29) in such manner as to make connection alternatively with either of the mentioned pairs of contacts. In order to prevent an automatic closing of the elevator circuit e, e' , by the action of gravity (in case of a burn-out in the coil C H) upon the cam bar 29, I may employ means such as the cam lock C L; and I may interpose, in the mentioned circuit e, e' , means such as the locking coil L C serving as an electro-magnet to withdraw the arm 37 of cam lock C L from engagement with a co- operating projection 38 upon the lever 35,— the weight of the overbalancing arm 39 being such as to retain the arm 37 in its engaging position and the circuit including contacts 32, 32' closed, except when the coil L C is energized.

In order to permit of the energizing of the cam helix C H (employed, as above described, to energize an actuator to operate both my gripping mechanism and my interlocking device) only when a car is suitably positioned opposite a floor, I may employ means such as are illustrated in Figs. 6, 7 and 8. At any suitable point, as near the front of the bottom of a car, I may support a zoning switch magnet or electro-magnet Z M, whose helix may be constantly energized by a circuit z, z' , the said electro-magnet being shown as pivotally mounted at 40 in such manner that the action of gravity upon the arm 41 and the zoning switch Z S carried thereby may be effective normally to hold said switch in its open position and out of engagement with the contacts 42, 42', by which a circuit e , through the magnetic cam helix C H, may be closed. To effect a closing of the zoning switch Z S when a car is suitably positioned at a floor level, I may provide, at each floor level, instead of an actual magnet or electro-magnet, a mere permeable element such as an iron plate 43, adapted to attract the magnet or electro-magnet Z M or an armature 44, rendered magnetic by the continuous supply of current through the mentioned circuit z, z' . By such a construction as I have described, it will be obvious that a zoning switch may be automatically closed at each floor level and otherwise held open.

In order to prevent the complete closing of a door which may be held open by the entrapping of a passenger therein, or as a result of any other accidental or deliberate act, I consider it advantageous to provide automatic means for interrupting the circuit to the door operating motor M whenever the

closing movement of the lever 15, or its equivalent, shall encounter exceptional resistance; and in Figs. 10 and 11, I have shown means for the purpose referred to comprising a rod 45, to which the lever 15 is pivotally connected at 46, this rod being shown as slidably mounted upon brackets 47, 48 and provided with a circuit closing element in the form of a spring-closed switch S S, controlling a relay circuit r, e herein- after referred to, by which the flow of current to the motor M may be controlled. As shown, a spring 49 may be effective normally to close a gap between the contacts 50, 50'.

My elevator circuit e, e' is intended to include not only the terminals 33, 33', adapted to be normally connected by the action of gravity upon the cam bar 29 (Fig. 9) and to be opened by the closing of a circuit through my magnetic gripper-cam, or its equivalent, but also an automatic elevator switch A E S, this switch being so constructed and positioned that it may be immediately opened upon the starting of the motor M, to open a door,—as by engagement of a projecting portion 51 of the rod 18, in the general manner diagrammatically suggested in Fig. 1.

In connection with any or all of the novel appliances above referred to, or their equivalents, I may employ usual or preferred types of manual control devices interposed respectively in the elevator circuit e, e' and in any suitable branches of a door-control circuit d, d' , within which the various mentioned electro-mechanical devices may be suitably interposed.

As best shown in the wiring diagram constituting Fig. 12, my door control circuit d, d' may advantageously be divided into branches including a relay circuit r, r' , a cam and gripper circuit e, e' and a motor circuit m, m' , in addition to the mentioned branch z, z' serving to energizing the zoning electro-magnet Z M; and although my motor M may be of any preferred type, I have suggested the employment of a motor provided not only with a series field S F, but also with a shunt field S H F in a separate branch circuit f, f' of the circuit d, d' . To provide for suitable control of the motor M by manual control means such as are indicated within the dotted line M C, I may include, in parallel branches of the relay circuit r, r' , an opening relay O R in a branch r, o , and a closing relay C R in a branch r, c , the opening relay O R being adapted, when energized, to move a switch O S into a position closing a branch circuit m, o of the motor circuit m, m' and thereby cause a flow of current through the motor M in such a direction as to effect a door-closing movement, and the closing relay C R being interposed in the second branch r, c of the circuit r, r' in such manner as,

when energized, to move the circuit closing element of the switch C S into a position favorable to a flow of current through the motor M in an opposite direction, to effect a closing of an elevator door.

To harmonize the operation of the opening and closing relays referred to with the energizing of the magnetic cam helix C H, I may provide the mentioned manual control device M C with a manual relay closing switch M R C S, brought into circuit closing position by a movement of the controller in one direction, and with a manual relay opening switch M R O S, closed by a movement in an opposite direction, the latter movement being incidentally effective to close also a manual cam switch M C S in the mentioned circuit e, e' by which the magnetic cam helix C H may be energized to effect a gripping of wire or cable 12 and a shift of my interlock.

To provide for automatic repetition or shifting of contacts by means supplemental to those described, and in order that no mere stretching or contraction of cable due to a change of load shall ever be effective, through the operation of a zoning switch, to deenergize my magnetic gripper-cam or actuator, I may provide, in a branch e a of the circuit e, e' an automatic cam switch A C S, adapted to be closed, by the door opening operation of the motor M, immediately after said motor has automatically opened the mentioned switch A E S in the elevator circuit e, e'; and I may interpose an automatic relay opening switch A R O S and an automatic relay closing switch A R' C S respectively in the mentioned branches r o, and r c of the relay circuit r, r', these last mentioned switches being so positioned as to be serially opened and closed by the further door opening movement of the motor M.

My above described elevator door control is especially suitable for use in connection with a single motor placed at the top of an elevator shaft; but it will be obvious that certain features of my invention are capable of advantageous use quite regardless of the position of the single motor required for the manipulation of all doors of a series, and regardless of whether this motor be secured upon a fixed or upon a movable foundation.

Although I have herein described one complete embodiment of my invention, it will be understood that various features thereof might be independently employed, and also that various modifications might be made, without the slightest departure from the spirit and scope of my invention, as the same is indicated above and in the following claims.

I claim as my invention:

1. In an elevator organization comprising a car and a plurality of doors at different floor levels and each provided with a driving bar, the combination of: a single door

motor, a vertically reciprocable motion-transmitting element movable therefrom, and means for connecting one of said door-driving bars at will to said reciprocable element, said means comprising jaws adapted to releasably grip said reciprocable element.

2. In an organization as set forth in claim 1, the combination of: electro-magnetic control means, comprising parts movably mounted on said car, for inhibiting the operation of said motor except when said car is stopped at a suitable level relatively to a floor.

3. In an organization as set forth in claim 1, the combination of: connecting means comprising an electro-magnetic gripper and means for energizing the same from said car.

4. In means for operating a plurality of elevator doors, the combination of: movable driving and self-locking bars pivotally connected to said doors, a vertically reciprocable transmission element extending opposite said doors, and means for operatively connecting any one of said bars with said reciprocable element, said means comprising jaws adapted to releasably grip said reciprocable element.

5. In an elevator organization, the combination of: an elevator circuit, a door-motor control circuit, and interlocking means comprising a magnetic cam for breaking one of said circuits and subsequently closing a branch of the other of said circuits.

6. In an elevator organization comprising a movable car and separate doors, self-locking driving bars extending across said doors and each having one of its ends pivoted to one side of a door and its opposite end pivoted to a vertically movable cross-head.

7. In an organization as described in claim 4, an overhead electric motor, motion transmitting means extending opposite all doors, and converting means for imparting therefrom substantially harmonic motion to a door.

8. In an organization as described in claim 5, means for preventing a failure of current energizing said magnetic cam after a door opening movement has been initiated.

9. In an organization as described in claim 5, a cam helix whose energization is effective both to grip a motion-transmitting element and to open an elevator circuit.

10. In an organization as described in claim 5, electro-magnetic gripping means operatively connected with a cam for moving an interlock controlling a relay circuit.

11. In a system for the electrical control of elevators and elevator doors, the combination of: an elevator circuit, a door-control circuit, interlocking circuit control means between said circuits, and means for preventing the shifting of said interlock-

ing means, under the action of gravity, when one of said circuits is burned out.

12. In a system for the electrical control of elevators and elevator doors, the combination of: a door-control circuit, manual means for closing said circuit, a motor operatively connected with means for transmitting movement to any of said doors and provided with means for successively opening an elevator circuit and closing a magnetic cam circuit.

13. In a system as described in claim 12, means whereby the continued operation of said motor may open one motor-control circuit, and thereafter close another motor-control circuit.

14. In an organization as described in claim 12, the combination of: means whereby the initiation of the mentioned movements may depend upon the suitable positioning of an elevator car at a floor level.

15. In an organization as described, in claim 12, means for maintaining a circuit controlling the flow of current to said motor open whenever a door is prevented from closing.

16. In an electric control for an elevator, an elevator circuit, a magnetic actuator circuit, an interlock capable of gravity restoration and gravity means for locking said

interlock against operation in the absence of current in said magnetic actuator circuit.

17. In an electric control for elevator doors, a magnetic actuator on a car, and means for opening a door upon the energizing of said actuator and an interlock mounted on the car and adapted to be actuated by said actuator.

18. In an organization as described in claim 17, means for energizing a door-opening motor upon the energizing of said actuator.

19. In an organization as described in claim 17, means whereby, upon the de-energizing of said actuator, a door may be closed either by a motor or by gravity means.

20. In an electric elevator door control, a zoning switch and manual control means on a car, a magnetic actuator energized by said manual control, and means for maintaining a current established by said magnetic actuator regardless of a subsequent automatic opening of said zoning switch.

In testimony whereof, I have hereunto set my hand at Los Angeles, California, this 14th day of May, 1924.

FREDERICK F. BRUSH.

Certificate of Correction.

It is hereby certified that in Letters Patent No. 1,588,007, granted June 8, 1926, upon the application of Frederick F. Brush, of Los Angeles, California, for an improvement in "Electrically-Operated Elevator-Door Controls," errors appear in the printed specification requiring correction as follows: Page 5, line 108, claim 7, strike out the word "overhead"; page 6, line 22, claim 15, strike out the comma; and that the said Letters Patent should be read with these corrections therein that the same may conform to the record of the case in the Patent Office.

Signed and sealed this 20th day of July, A. D. 1926.

[SEAL.]

M. J. MOORE,
Acting Commissioner of Patents.
